WALL TELEPHONE SUPPORT

Felix Gilbert, New York, N.Y., assignor to General Alarm Corporation, New York, N.Y., a corporation of Delaware

Filed Oct. 24, 1966, Ser. No. 4,406

Term of patent 14 years

(Cl. D26—14)

FIG. 1 is an elevational view of a wall telephone support embodying my new design;

FIG. 2 is a side elevational view of the support illustrated in FIG. 1;

FIG. 3 is a top plan view of said support; and

FIG. 4 is a fragmentary cross sectional view taken along the lines 4—4 of FIG. 1.

The broken lines are shown for purposes of illustration only.

I claim:

The ornamental design for a wall telephone support, as shown and described.
